ROBERT G. ARCHER, SR., AND ROBERT G. ARCHER, JR., OF FORT WASHINGTON,
PENNSYLVANIA.

ADJUSTABLE LAMP BRACKET.

Application filed December 23, 1921. Serial No. 525,451.

To all whom it may concern:

Be it known that we, ROBERT G. ARCHER, Sr., and ROBERT G. ARCHER, Jr., citizens of the United States, residing at Fort Washington, in the county of Montgomery and State of Pennsylvania, have invented new and useful Improvements in an Adjustable Lamp Bracket, of which the following is a specification.

10 Our invention relates to new and useful improvements in an adjustable lamp bracket, particularly adapted to hold an electric light in different positions, and has for its object to provide in such a device a unique construction that will give to the bracket an extra large range of adjustment.

Another object of our invention is to produce a ball and socket joint of peculiar and unique construction.

20 A further object of the invention is to provide a clamp for such a device that may be readily adjusted to fit objects of different sizes to which the bracket is to be attached.

A still further object of the invention is 25 to construct a bracket of the class stated consisting of a body having clamp members of jaws connected therewith, one of which is operable by means of a cam, a ball supported by said body, socket elements cooperating with said ball, a separator connected with said socket elements and having means to adjust the tension of the latter, another ball carried by portions of the socket elements, a socket hook holder and socket hook 30 coacting with the last named ball, said holder having means to vary the tension of the socket hook, and means on the body and the socket hook holder for supporting the conductor wires leading to a lamp supported in the socket hook.

With these ends in view, this invention consists in the details of construction and combination of elements hereinafter set forth and then specifically designated by the 45 claims.

In order that those skilled in the art to which this invention appertains, may understand how to make and use the same, we will describe its construction in detail, referring by numerals to the accompanying drawings forming a part of this application, in which:

Fig. 1, is a plan view of an adjustable

lamp bracket made in accordance with our invention.

55

Fig. 2, is a side elevation thereof showing a lamp socket bulb attached thereto.

Fig. 3, is a side elevation of the separator.

Fig. 4, is an edge view thereof.

Fig. 5, is a side elevation of the socket hook holder.

Fig. 6, is an edge view thereof.

Fig. 6^a is an end view of the same.

Fig. 7, is an edge view of one of the rubber caps.

65

Fig. 8, is a face view thereof.

Fig. 9, is a side elevation of the cam for actuating one of the jaws.

Fig. 10, is an edge view thereof.

Fig. 11, is a side elevation of the upper clamp jaw.

Fig. 12, is a lower face view thereof.

Fig. 13, is a plan view of the lower clamp jaw.

Fig. 14, is a side elevation thereof.

75

Fig. 15, is a side elevation of the body.

Fig. 16, is a section at the line 16—16 of Fig. 15.

Fig. 17, is a lower end view thereof.

In carrying out our invention as here embodied, 2 represents the body including a leg 3 T-shaped in cross section, as plainly shown in Fig. 16, and an integral outwardly projecting head 4 having a recess 5 at its outer end from which projects the trunnion 6 and on this trunnion is journaled the cam 7 by means of the hole 8, said cam having a handle 9 whereby the same may be readily rotated. The trunnion 6 has a slot 10 therein for the reception of one of the ball supporting members 11, the other or co-acting one of said members lying between the pair of coacting lugs 12 formed on the other side of the head 4 directly opposite the aforementioned trunnion, and portions 95 of these ball supporting members underlie the lugs 13 and 14 which are arranged in pairs and project from opposite faces of the head. A bolt passes through the trunnion and has a nut threaded on its opposite end 100 and the head of said screw engages the other to assist in holding said members in place, while another bolt 15' passes through the head in the region of the lugs 15 and has a nut 16' threaded thereon, said bolt nut 105 engaging the said ball supporting members

at another point to further assist in holding the ball supporting members in place, while the lugs 15 act as stops to prevent the nut 10 being drawn too tightly against the parts.

A ball 16 is carried by the ball supporting members 11 and as said ball supporting members are preferably of wire they are preferably inserted in holes in the ball and afterwards fastened in any suitable or well known manner.

With the upper edge of the head 4 are formed the pair of horns 17 producing an aperture 18 with a restricted mouth 19 whereby a conductor wire may be readily inserted and will be prevented from accidental withdrawal under ordinary conditions.

About the ends of the ball supporting members 11 are coiled the springs 20, the upper ends of which are fastened to the screw passing through the trunnion or other suitable part as the stationary element, while the other ends are fastened to the upper jaw 21 in any suitable and well known manner. The said upper jaw has an upright portion 22 in which are formed the vertical grooves 23 for registration with the ends of the ball supporting members 11 having the springs 20 coiled thereon whereby the upper jaw will be guided during its movements caused by the cam 7 or the counter movements caused by the action of the springs.

On the leg 3 is slidably mounted the lower jaw 24 which has undercut or beveled notches 25 for registration with the flanges of the T shaped leg so that when pressure is brought to bear upon the jaw it will be tilted so as to firmly grip the flanges of the leg and be prevented from slipping. Both the upper and lower jaws are beveled as at 26 so as to form a tenon for coaction with the dove tailed groove in the rubber caps 27 which are mounted on the jaws to prevent the latter marring the object to which the lamp bracket is fastened. In order to prevent the lower jaw becoming disengaged from the leg of the body a pin 28 or its equivalent is fixed to the lower end of the leg after the lower jaw has been placed thereon.

The reference numeral 29 denotes the reach consisting of a separator 30, the reach arms 31 and the ball 32. The separator is preferably in the form of a casting having a projection 31' at one end, one edge of which is concave as at 32' with a threaded hole 33 for the reception of screws 34 or equivalent fastening devices. Above and below the projection 31' and slightly to the rear thereof on each side of the separator are formed shoulders 34' and at the other end adjacent opposite longitudinal edges 65 and projecting from each face are formed

the lugs 35 and in the region of said lugs are formed holes 36.

The reach arms 31 each have a loop 37 formed at one end with a tail 38 projecting therefrom parallel with the arm proper 70 and these arms of which there are two are mounted upon the separator with the arm proper on one side thereof and the tail on the opposite side and these parts rest upon the shoulders 34' and engage the inner walls 75 of the lugs 35 and are held in place by the screws 34 and other screws threaded into the holes 36. The loops 37 project beyond the end of the separator and form a socket for the ball 16 mounted therebetween and 80 by regulating the screws 34 the tension of the loops upon the ball 16 may be varied as will be obvious. The ball 32 is fastened to the outer ends of the reach arms in any suitable or well known manner.

The socket hook holder 39 is provided at one end with an arcuate lug 40 forming a portion of a socket and this lug is preferably wedge shaped lengthwise, as shown in Fig. 1. The inner surface of said lug 90 is preferably concaved to receive the ball 32 and below said lug are formed the ears 41 producing channels in which rest the parallel shank portions 42 of the socket hook 43 having at one end the loop 44 for coaction with the arcuate lug 40 to produce a socket for the ball 32, while at the other end is formed the hook or spring clamp 43 to receive a suitable lamp socket 45 in which a lamp 46 is adapted to be inserted. The 100 parallel shank portions of the socket hook are situated on opposite sides of the socket hook holder and at one end lie between lugs 49' and are held in place by a screw 47 passing through a hole in the holder and having a nut 48 thereon, said nut engaging one of the shanks while the head of the screw engages the other and in order to prevent said screw nut being drawn too tightly against the socket hook, lugs 49 are formed 105 on the holder of a length approximating the thickness of the material from which the socket hook is produced, while at the other end a screw 50 is inserted between the shank portions of the socket hook and threaded into the holder and by regulating said screw the tension of the loop on the ball 32 may be varied. In the body of the holder is formed a notch or aperture 51 having a restricted mouth 52 formed by the 110 horns 53 whereby a conductor wire may be inserted and will not become accidentally displaced.

By constructing a lamp bracket this way the light may be adjusted to numerous different positions according to conditions and desires of the user, it being practically possible to obtain an almost universal adjustment by the use of the two balls and their coacting sockets.

In use the lower jaw 24 of the clamp is adapted to be positioned vertically upon a leg 3 so that it will be spaced from the upper jaw 21 a distance approximating the thickness of the object to which the device is to be attached and then by actuating the cam 7 the said upper jaw will be moved a sufficient distance to securely clamp the device in place and during this action the lower jaw will be slightly tilted so as to firmly grip the flanges of the leg 3 and thus prevent said lower jaw from slipping from its adjusted position until the upper jaw is released. After the lamp bracket is clamped in place the parts may be readily adjusted by swinging the reach about the ball 16 and the socket hook holder and its component parts about the ball 32.

Of course we do not wish to be limited to the exact details of construction as herein shown as these may be varied within the limits of the appended claims without departing from the spirit of our invention.

Having thus fully described our invention, what we claim as new and useful, is:—

1. An adjustable lamp bracket consisting of a body, clamping jaws carried thereby, ball supporting members carried by said body, a ball attached to said members, a separator, reach arms adjustably attached to said separator and having loops to engage said ball, another ball carried by the outer ends of said reach arms and a socket hook holder, a portion of which forms a part of a socket for coaction with the last named ball, and a socket hook adjustably connected with said holder and having a loop at one end for coaction with the last named ball to complete the socket therefor.

2. An adjustable lamp bracket including a body comprising a leg T-shaped in cross section and a head, the latter having a recess in one face at its outer end and provided with a notch having a restricted mouth at its outer end, a trunnion formed integral with the head in the region of the recess and having a notch in its outer end, a pair of lugs projecting from said head opposite the trunnion, other lugs formed with said head and projecting from opposite faces thereof, a ball supporting member on each side of said head underlying certain of said lugs with a portion of one of said members lying in the notch in the trunnion and a portion of the other supporting member lying between the lugs on the opposite side thereof, a cam rotatably mounted on said trunnion, means passing through the head in the region of the trunnion to hold the ball supporting means in place, other means mounted on the head and engaging portions of the ball supporting means and also certain of said lugs, an upper jaw having a shank with grooves for registration with portions of said ball supporting means and adapted to be moved in one direction by the cam, means to normally force said jaw in the opposite direction, a lower jaw slidably mounted on the leg, means fixed to said leg to prevent the accidental displacement of said lower jaw, resilient caps on said jaws, a ball fastened to the ball supporting means, a reach coacting with said ball, said reach including another ball, a socket hook holder and a socket hook adjustably attached to the holder, said holder and hook forming a socket to cooperate with the last named ball.

3. An adjustable lamp bracket including a body comprising a leg T-shaped in cross section and a head, the latter having a recess in one face at its outer end and provided with a notch having a restricted mouth at its outer end, a trunnion formed integral with the head in the region of the recess and having a notch in its outer end, a pair of lugs projecting from said head opposite the trunnion, other lugs formed with said head and projecting from opposite faces thereof, a ball supporting member on each side of said head underlying certain of said lugs with a portion of one of said members lying in the notch in the trunnion and a portion of the other supporting member lying between the lugs on the opposite side thereof, a cam rotatably mounted on said trunnion, means passing through the head in the region of the trunnion to hold the ball supporting means in place, other means mounted on the head and engaging portions of the ball supporting means and also certain of said lugs, an upper jaw having a shank with grooves for registration with portions of said ball supporting means and adapted to be moved in one direction by the cam, means to normally force said jaw in the opposite direction, a lower jaw slidably mounted on the leg, means fixed to said leg to prevent the accidental displacement of said lower jaw, resilient caps on said jaws, a ball fastened to the ball supporting means, a reach coacting with said ball, said reach including another ball, a socket hook holder and a socket hook adjustably attached to the holder, said holder and hook forming a socket to cooperate with the last named ball.

4. In a device of the character stated, a body having clamping elements, a ball supported by said body, a reach consisting of a separator and a pair of reach arms, said arms each having a loop formed at one end and coacting to produce a socket for said ball.

5. In a device of the character stated, a body having clamping elements, a ball supported by said body, a reach consisting of a separator and a pair of reach arms, said arms each having a loop formed at one end and coacting to produce a socket for said ball.

ball, means to vary the tension of said loops on said ball, another ball carried by the opposite ends of the reach arms, a socket hook holder having a portion of a socket formed therefrom, a socket hook carried by said holder, said socket hook having a loop formed therewith for coaction with the aforementioned socket part to form a socket

for the last named ball, and means to vary the tension of said loop on said last named ball.

In testimony whereof, we have hereunto affixed our signatures:

ROBERT G. ARCHER, SR.
ROBERT G. ARCHER, JR.
